UNITED STATES PATENT OFFICE.

ARCHIBALD D. METHVEN, OF DETROIT, MICHIGAN, ASSIGNOR TO FISHER BODY COMPANY, OF DETROIT, MICHIGAN, A CORPORATION OF MICHIGAN.

CARRIAGE-DOOR BUMPER.

1,072,141.

Specification of Letters Patent.

Patented Sept. 2, 1913.

Application filed March 17, 1913. Serial No. 754,730.

To all whom it may concern:

Be it known that I, ARCHIBALD D. METHVEN, a citizen of the United States of America, residing at Detroit, in the county of Wayne and State of Michigan, have invented certain new and useful Improvements in Carriage-Door Bumpers, of which the following is a specification, reference being had therein to the accompanying 10 drawings.

In the use of bumpers or anti-rattling devices for doors for automobiles, cars or other vehicles, the wear on the cushion member is frequently such that the device 15 becomes inoperative after a short period.

This invention relates to bumpers of this character and to an arrangement thereof whereby means are provided for quick adjustment to compensate for wear so that the 20 device is always operative.

The invention consists in the matters hereinafter set forth and particularly pointed out in the appended claims.

In the drawings, Figure 1 is a view in 25 longitudinal section of a bumper that embodies features of the invention; Fig. 2 is a view in end elevation thereof; Fig. 3 is a view in cross section through a closure and frame or jamb therefor showing the application of one form of the device; and Fig. 4 is a similar view showing another 30 method of applying the bumper.

Referring to the drawings, a suitable base plate 1 has an upturned flange or face plate 2 with a guide aperture therein through which a buffer block 3 of rubber or other like elastic material may be projected. A thrust plate 4, to which the block is cemented or otherwise suitably secured at 35 its inner end, rides near each end on screws 5 whose outer heads 6 are preferably flush with the face plate 2 and whose inner end portions are journaled in suitable guide openings in a rear flange 7 of the base. The 40 screws may be slightly headed over to retain them in the rear flange if desired, the buffer block 3 and the thrust block 4 constituting a buffer unit. The thrust plate itself 45 may be in screwthreaded engagement with the members 5, or preferably, nuts 8 may be employed that bear directly against the back of the thrust plate and have a longer 50 engagement with the screw.

The base may be held on the jamb member 9 of a door frame or casing, as by suit-

able screws 10 or the like in such manner that the buffer lies in the path of the stop 11 or marginal portion of the closure or door. As the buffer block wears, it may be moved out farther into the path of the closure by turning the screws with a suitable implement. Or as indicated in Fig. 4, the base may be so applied in such manner to a casing 12 that the buffer block 3 acts not only as a cushion but also as a frictional stop to the door, by bearing against the marginal face 13 of the latter.

As a result of this construction a bumper for doors, gates or closures of like character is obtained in which a quick adjustment is provided for positively moving the buffer block into the desired position in the path of the opposing door or like movable member and holding it in such position.

Obviously, changes in the details of construction may be made without departing from the spirit of my invention and I do not care to limit myself to any particular form or arrangement of parts.

What I claim is:

1. A bumper comprising a casing, a buffer block reciprocable through an opening in the casing, a thrust plate carrying the buffer block, and members in screwthreaded engagement with the thrust plate for securing the plate and buffer block in adjusted position.

2. A bumper comprising a base, a face plate on the base, a rear flange on the base, a pair of screw members journaled in parallel relation between the face plate and flange, a thrust block in screwthreaded engagement with the members, and a buffer block extending from the thrust plate to which it is secured through a guide opening in the face plate.

3. The combination with a door and a casing therefor, of a bumper consisting of a base adapted to be secured on one of the opposing faces of the door and casing, a buffer block reciprocable through an opening in the base into the path of motion of the opposing face, screw members rotatable in the base, and a thrust plate in screwthreaded engagement with the members secured to the buffer block to shift the latter through the opening.

4. A bumper comprising a base having a face plate and a rear flange, a buffer block reciprocable in an opening through the face

plate and adjusting means rotatable in the base in screwthreaded engagement with the face plate for shifting the buffer.

5. A bumper, having in combination, a base comprising a casing with a face plate having an opening therein, a buffer unit having a portion projected through said opening, said buffer unit adapted to act as a cushioning member, and means journaled 10 to rotate in the base and in screw-threaded engagement with the buffer unit, the said

means having a head projecting through the face plate of the base, whereby the buffer unit may be adjusted with respect to the base from the outside of the casing 15 forming the base.

In testimony whereof I affix my signature in presence of two witnesses.

ARCHIBALD D. METHVEN.
